UNITED STATES PATENT OFFICE.

JOSEPH ZUBATY, OF FLINT, MICHIGAN.

INSTRUMENT BOARD.

Application filed March 27, 1926, Serial No. 97,941. Renewed January 9, 1929.

This invention relates to instrument panels and particularly to panels of the type disclosed in my prior application Ser. No. 47,058, filed July 30, 1925. In this type of assembly 5 the instruments are so arranged that light may be projected onto the instrument dials from the rear of the instrument board so that none but diffused, reflected light reaches the eyes of the observer. In the assembly disclosed 10 in my prior application provision is also made for the illumination of the driver's compartment, and particularly of the transmission lock and control levers. The present invention consists of a simplification of the construction shown in my prior application 15 in that a separate mounting for the lamp is dispensed with, one of the parts customarily provided to secure the instruments in position being used to support the lamp. So far as this feature is concerned the invention is 20 of general application: thus, while I have shown it applied to a construction in which the housings of the instrument are provided with windows through which light may be 25 projected upon the dials, my construction is of equal utility where some other provision is made for the transmission of light to the faces of the instruments.

Another feature of my invention consists 30 in the manner of mounting the instrument panel, which carries the instruments, upon the instrument board. My construction is such that none of the securing means are visible while at the same time the instrument 35 panel is firmly yet somewhat resiliently secured in position. The details of this feature of the invention, as well as the means for illuminating the panel, will be made clear in the following description.

40 In the drawings:

Figure 1 is a front elevation of my panel as it appears mounted on the instrument board.

Figure 2 is a rear view of Figure 1.

45 Figure 3 is a view corresponding to Figure 2 with certain parts removed and the instrument housings shown in partial section to show the windows provided therein.

Figure 4 is a section on line 4—4 of Figure 2.

50 Figure 5 is a rear elevation of the instrument panel with the instruments removed.

Figure 6 is a section on line 6—6 of Figure 2.

55 Figure 7 is a section on line 7—7 of Figure 1.

Figure 8 is a section on line 8—8 of Figure 1.

The reference character 2 indicates an instrument board such as is provided upon automobiles of conventional construction. 4 indicates the instrument panel upon which the instruments are assembled prior to the mounting of the panel on the instrument board. The instrument board is provided with an opening 8 which snugly receives the bead 10 formed on the panel. A flange 12 extends outwardly from the bead 10 and engages the rear face of the instrument board and from the flange extend rearwardly and outwardly projecting ears 14. The ends of the ears 14 are apertured for the passage of the shanks of screw bolts 16, the heads 17 of which are secured in pockets formed by welding apertured strips 18 to the rear face of the instrument board. Nuts 20 on the shanks of the bolts 16 serve to clamp the ears to the bolts and yieldingly hold the panel in position on the instrument board.

The instrument panel is provided with 50 apertures for the display of the instruments, such as the clock 22, ammeter 24, oil gage 26, gasoline gage 28, and speedometer 29. Each of these instruments is provided with a bezel portion projecting into the corresponding 55 aperture in the panel. The means for clamping the instruments in position comprises screw bolts 30 projecting through the flange 12 of the panel and having their heads concealed between the flange and the instrument 60 panel, and screw bolts 32 secured to the rear of the panel, preferably in the same manner that bolts 16 are secured to the rear of the instrument board. If desired other fastening means, such as hook devices, clamps, or the like, may be substituted for the screw bolts.

Clamping plates 34 are apertured at their ends to pass over the shanks of screw bolts 30 and 32 and are drawn tightly against the backs of the instruments by a manipulation 65 of suitable nuts threaded on the bolts. It will be noted that certain of the bolts carry the ends of several of the clamping plates and that the instruments are so arranged and the clamps so positioned and designed that portions of certain of the clamping plates marked 34' bridge the space between adjacent faces of certain of the instruments. These portions of the clamps have been utilized for the supporting of spring clips 36 70 designed to receive and grip the beads 38 formed on lamp sockets 40 in which lamps 42

are detachably secured in the usual manner. With this construction when it is desired to inspect or replace a lamp it is merely necessary to withdraw the lamp and socket rearwardly from the clip, the flexible conductor 43 permitting these parts to be extended forwardly of the instrument board to a convenient position for manipulation.

Each of the instrument casings is provided 10 with a window consisting of an aperture in the casing covered by a sheet of translucent material, such as paper, indicated at 44, held in position by a frame 46 riveted to the casing. The light from the bulb 42 is adapted 15 to pass through the windows and illuminate the instrument dials as in my pending application Ser. No. 47,058, previously referred to. The exteriors of the instrument cases and of the clamping plates and the rear face of 20 the instrument panel are preferably nickelized, painted white, or otherwise treated to provide a good light reflecting surface so that a portion of the light from the bulb is projected downwardly to illuminate the driver's 25 compartment.

In Figures 7 and 8 I have shown some examples of special treatment of instrument housings to provide the windows for the transmission of light to the dials or other indicating parts. Thus in the construction in Figure 7 I have provided the clock 22 with special bezel 50 carrying a transparent plate 52 for the display of the clock dial, the bezel being of greater than normal length and provided with a window 54 in the side thereof through which light may be projected upon the dial.

In Figure 8 I have shown a commercial type of gasoline gage comprising a glass tube 60 containing colored indicating fluid the level of which indicates the height of the gasoline in the supply tank in accordance with the markings shown at 64 on face plate 66 secured over the instrument housing 68. This housing is provided with the window 70 which permits the projection of light upon the tube 60 at the rear of the face plate. Some of this light passing by reflection and refraction through the tube falls upon the markings 64 upon the face plate and renders the instrument easily readable.

It will be noted that while the speedometer is provided with studs 72 passing through apertures in the corresponding clamping plate 34 and these studs carry thumb nuts 74 for positively securing the speedometer to the clamping plate, the other instruments are held in place by clamping action only the clamps preferably being provided with cut-out portions 76 to engage studs or bolts projecting from the casings to hold the instruments against rotation on the panel.

It will be noted that my lighting arrangement requires no special parts for its support,

the brackets used to hold the socket receiving clips being those customarily employed to hold the instruments in position. It will also be noted that this feature of the invention is of utility whether the instruments be mounted directly upon the instrument board or 70 panel with which automobiles are customarily provided or whether it be mounted upon an auxiliary panel, such as that shown at 4 which in turn is mounted upon the instrument board. 75

Attention is called to the fact that the method of supporting the panel upon the instrument board is such that the panel is held with a certain degree of resiliency thereby lessening the effects of jarring upon the mechanisms of the instruments. The panel also presents a very attractive appearance, no fastening devices being visible and the character of the illumination is such that the instruments may remain lighted during night driving without causing any annoyance to the driver or distracting his attention from the road. 80

I claim:

1. The combination of an instrument panel, an instrument, a clamping member at the rear of the panel arranged to clamp the instrument to the panel in position so that its dial may be observed, said instrument being so arranged that light may be projected upon the dial from the rear of the panel, and a lamp supported on said clamping member and adapted to illuminate the dial. 90

2. The combination of an instrument board having an opening therein, an instrument panel adapted to support a plurality of instruments, said panel having a portion adapted for display in said opening and another portion for abutment against the rear face of the instrument board, means for securing the panel in position and fastening means for securing the instruments on the panel comprising parts secured to the said second named portion of the panel and concealed by said instrument board. 95 100 105

3. In the combination as defined in claim 2, the means for securing the panel in position comprising ears projecting outwardly from said second named portion of the panel and adapted for engagement by clamping devices extending rearwardly from the instrument board. 110 115

4. The combination of an instrument board having an opening therein, an instrument supporting panel adapted to be secured over said opening, said panel comprising a sheet metal member having a portion adapted to extend into and fill said opening, a flange portion extending from said first named portion and adapted to bear against the rear face of said instrument board, rearwardly and outwardly extending ears projecting from said first named portion, and 120 125

fastening devices secured to said instrument board and adapted to cooperate with said ears for securing the panel in position.

5. An instrument comprising a casing, a transparent tubular liquid containing member in the casing, and a face plate having a slot therein for the display of the said member, the edges of the face plate defining the said slot bearing graduations, and an aperture in the casing at the rear of the face plate and at one side of the slot for the illumination of the tubular member. said tubular member serving to transmit rays of light to the face plate.

15 6. The combination of an instrument panel, a plurality of instruments each comprising indicating means and a casing having an aperture for the display of the indicating means, said casing being provided with 20 a second aperture for the projection of light from without the casing upon the indicating means for rendering the latter visible through said inspection aperture. clamping means at the rear of the panel arranged to 25 clamp the instruments to the panel in position so that their indicating means may be observed, and a lamp supported on said clamping means and arranged to project light through said second named apertures 30 to render the indicating means visible through the first named aperture.

7. The combination of an instrument panel, a plurality of instruments mounted for display on the panel, said instruments being arranged so that light may be projected upon the dials thereof from the rear of the panel, clamping devices adapted to secure said instruments in position, a lamp supported on one of said clamping devices and arranged to illuminate the dials of the instruments, the exteriors of said instruments being provided with light reflecting surfaces so that a considerable portion of the light from the lamp is projected downwardly between the instruments into the driver's compartment.

8. The combination of an instrument board having an opening therein, an in-

strument panel formed of sheet metal and provided with an apertured portion for display in the opening, said portion being provided with a peripheral bead fitting said aperture, said bead being provided with a marginal portion adapted to engage the rear face of the board, and means for clamping the panel against the board.

9. An instrument assembly comprising a casing having an instrument therein, said instrument being provided with indicating means, a cover for the casing, comprising a body portion and an annular flange surrounding the body portion, extending rearwardly therefrom, and engaging the casing for securing the cover in position, said body portion being provided with an aperture for the display of the indicating means, transparent medium mounted in the cover and sealing the aperture against the entrance of dust, said flange being provided with an aperture for the projection of light upon the indicating means at the rear of the first named aperture, and a transparent cover for said second named aperture.

10. An instrument assembly comprising a casing having an instrument therein, said instrument being provided with indicating means, a cover for the casing comprising a body portion and an annular flange surrounding the body portion, and extending rearwardly therefrom and engaging the housing for securing the cover in position, said body portion being provided with an aperture for the inspection of the indicating means, the part of the body portion surrounding said aperture being offset from the plane of the remaining portion to facilitate alignment with an opening in the instrument panel, a transparent cover for said aperture, said flange being provided with an opening for the projection of light upon the indicating means at the rear of the first named aperture, and a transparent cover for said second named aperture.

In testimony whereof I affix my signature.

JOSEPH ZUBATY.
